UNITED STATES PATENT OFFICE.

ROBERT GOULD JENNINGS, OF ELMIRA, NEW YORK.

YARN CLEANER.

Application filed August 10, 1921. Serial No. 491,152.

To all whom it may concern:

Be it known that I, ROBERT GOULD JENNINGS, a citizen of the United States, residing at Elmira, in the county of Chemung and State of New York, have invented certain new and useful Improvements in Yarn Cleaners (for which I have filed applications in Canada, February 5, 1915, Patent No. 164,527, of August 24, 1915; and in 5 England, March 3, 1915, Patent No. 3,421 of 1915; and in Germany, March 6, 1915, Patent No. 295,197, of November 11, 1916; and in Switzerland, March 13, 1915, Patent No. 73,091, of August 16, 1916; and in 10 Austria, March 13, 1915, Patent No. 71,776, of May 25, 1916; and in France, March 24, 1915, Patent No. 478,966, of November 2, 1915; and in Italy, March 30, 1915, Patent No. 144,445; and in Japan, March 18, 1915, 15 Patent No. 28,622, of November 4, 1915); of which the following is a full, clear, and exact description, such as will enable others skilled in the art to which it pertains to make and use the same.

25 This invention relates to yarn cleaning apparatus, and more particularly in some of its details, to apparatus for removing from a running thread of yarn slubs and similar impurities, such as fragments of 30 fibers, seeds, burrs, leaves, and the like, and relates further to improvements in yarn cleaning apparatus such as disclosed in Patent No. 1,301,133, granted to R. G. Jennings on April 22, 1919, reissued March 16, 1920, 35 No. 14,818.

It is an object of the invention to improve and perfect yarn cleaning apparatus of the class mentioned so as to accomplish the most satisfactory results in operation.

40 Another object is to provide improved yarn cleaning apparatus of the class mentioned well adapted to remove impurities from a running thread of yarn in an effective and satisfactory manner while maintaining uniform tension on the yarn.

45 It is a further object to provide an improved releasing means for a yarn cleaning unit of the general type disclosed in said prior patent.

50 A further object is to provide an improved yarn cleaning apparatus which automatically accommodates itself to variations in the diameter of yarn maintaining uniform tension thereon and minimizing the 55 breakage thereof.

Still another object is to provide a yarn cleaning apparatus having relatively few parts which are readily assembled or disassembled in a short space of time by ordinary workmen requiring no special skill 60 therefor, and which is susceptible of easy repair.

The invention accordingly consists in the features of construction, combinations of elements and arrangement of parts which 65 will be exemplified in the construction hereinafter set forth, and the scope of the application of which will be indicated in the following claims.

In the accompanying drawings wherein 70 several illustrative embodiments of the invention are disclosed,

Figure 1 is a fragmentary plan view showing an assembly of a plurality of groups of 75 cleaning units with common means for operating the same;

Fig. 2 is a sectional elevation taken approximately on the line 2—2 of Fig. 1, looking in the direction of the arrow;

Fig. 3 is a sectional view similar to Fig. 80 2, showing a modified construction;

Fig. 4 is an enlarged detail fragmentary view showing details of construction of the cleaning unit employed in Figs. 1-3;

Fig. 5 is a view similar to Figs. 2 and 3, 85 but showing a modified construction;

Fig. 6 is an enlarged fragmentary elevation of one of the cleaning units shown in Fig. 5; and

Fig. 7 is a sectional view on the line 7—7 90 of Fig. 6.

Referring now to the drawings for a detailed description, and first to the embodiment of Figs. 1, 2, and 4, each of a plurality of rectangular supporting bars 1 carries six 95 cleaning units 2 arranged in spaced series along the length thereof, and is provided at its forward end with a tension device 3 of any desired form through which the running yarn 4 may pass. There may be provided as many of these bars 1 as desired, each with its series of cleaning units as described, and placed side by side, and arranged to be simultaneously operated by a shaft 5 extending adjacent to the ends of 100 the bars 1.

The construction of each individual cleaning unit 2 is similar in general to those disclosed in said reissued Patent No. 14,818. Two modifications of this cleaning unit are 110

herein disclosed, one being shown in Fig. 4 and another in Figs. 5, 6, and 7. The blade construction and means for gripping and holding the impurities are similar in both of these forms, but the releasing mechanism and other details differ. As shown in these figures, each unit comprises a pair of blades 6^a and 6^b mounted side by side and having downwardly curved rearwardly extended portions 7 contacting with a base or bed 8 secured to the supporting bar 1. This bed has a generally horizontally disposed top portion merging with a downwardly and rearwardly curved portion, and the curvature of the bed is slightly different from that of the lower faces of the curved portions 7 of the blades, forming a curved, wedge-shaped slot between the bed and the blades for gripping and holding the impurities as the yarn moves past. The blades 6^a and 6^b are pivotally mounted side by side in pairs on spindles or pins 9 secured to the bar 1.

In the modification of the unit construction shown in Fig. 4 the mounting of the blades on the pin 9 may be similar to that disclosed in said reissue patent or as herein-after described in connection with Figs. 5, 6, and 7. The arrangement of the springs for keeping the blades pressed against the bed is not shown in Fig. 4, but it will be understood that they may be mounted upon the pins 9 and connected to the blades. The means for operating the blades employed in this modification will be hereinafter described.

In the modification of unit construction shown in Figs. 5, 6, and 7, a spacing washer or sleeve 10 is disposed on the pin 9 between the bar 1 and the face of the blade 6^b, and a block 11 is secured on the end of the pin on the opposite side of the bar 1 by a screw. The opposite end of the pin is threaded and a nut 12 thereon engages the blade 6^a holding the parts in assembled relation. The blades are pivotally mounted on pin 9, which may be non-rotatably mounted in the bar 1, and are urged to contacting position with the bed 8 by a coiled spring 13 having oppositely disposed coils 13^a and 13^b disposed on the pin 9 between the blades, the outer ends thereof being bent to engage the respective blades. The two coils are preferably made up of a single piece of spring-wire, which is bent into an integral loop 14 around the tension lever 15 pivoted to the pin between the loops of the spring. This spring is also adapted to hold the blades in properly spaced relationship, to accommodate different diameters of yarn, and to hold them yieldingly in position so enlargements or other imperfections on the yarn may pass without causing excessive tension or strain, either on the yarn or on the parts. The spacing of the blades may be adjusted by means of the nut 12.

When the yarn 4 is passed between the blades it is lightly pressed therebetween under the influence of the spring 13, the pressure exerted upon the blade being readily adjustable by means of the nut 12, and by the same means the blades may be adjusted for different sizes of yarn. Irrespective of the size of yarn or of the irregularities of the same, this spring holds the blades lightly in yielding engagement with the yarn at all times, and any movement of the blades due to enlargements or the like on the yarn is yieldingly opposed by the spring by reason of the fact that the lower portions of the blade fulcrum over the spacing sleeve 10 on one side or the nut 12 on the other side. The tendency, therefore, is to offer a constant resistance to the passing yarn and to maintain as nearly as possible a uniform tension thereon.

A detailed description of the operation of the type of blade construction and arrangement disclosed in Figs. 4 to 7 in removing impurities from the traveling yarn is fully described in said re-issue patent and there is no need, therefore, to enter into a detailed description here. It may be said, however, that the impurities removed from the yarn are lodged between the blades and beds 8 and released therefrom at intervals by certain mechanism hereinafter described.

Referring to Figs. 1 and 2, one form of mechanism for operating the cleaning units to release the impurities is shown. According to this construction improved means are provided for operating the blades of the units alternately in groups in order to aid in maintaining as nearly as possible a uniform resistance to the passage of the yarn, and maintaining in consequence an approximately constant tension at all times. As shown, brackets 16 are suitably spaced apart and mounted upon a supporting base 17 and are provided with aligned openings for the reception of a supporting bar 18 held in position in the brackets by set screws 19. A bracket arm 20 is supported from a block or hub 21 having a lower extension 22 provided with an open slot for receiving the supporting bar 18. A set screw 23 threaded in the projection is adapted to contact with the supporting bar to securely lock the hub in position thereon. The bracket arm is provided with a laterally disposed lug 24 for supporting one end of the bar 1, the other end of said bar being supported on the hub 21. Longitudinally reciprocable parallel rods 25 and 26 are mounted side by side in openings in the lug 24, the rear ends of these rods diverging for connection to the opposite ends of a rocker arm 27 pivotally mounted intermediate its ends on the hub 21. This rocker arm is provided with a medial, laterally extending operating lug 28 having its terminal formed with oppos-

ing symmetrically curved side faces. Disposed adjacent said operating lug and arranged to co-operate therewith is a pivoted lever 29 having a terminal adjacent said lug formed with curved side faces similar to and adapted to engage the curved faces of the operating lug. This lever is slotted at the opposite end to receive a pin 30 carried by a rocker arm 31 which is connected by an open slot and set screw 31^a with the rock shaft 5. Operating blocks 32 are adjustably connected with each of the rods 25 and 26, lying adjacent the operating arms 33 of the cleaning units so as to operate the latter when the rods are longitudinally reciprocated. In one embodiment, as shown in Fig. 4, each of these arms 33 is secured to the pin 9 of the corresponding cleaning unit, the pin being rotatably mounted in the bar 1 and the blades being secured thereto to rotate therewith. As shown in Fig. 2, the operating blocks are spaced on the rod 25 to contact with the operating arms of alternate cleaning units, and those on the rod 26 are spaced to contact with the arms of the remaining units.

The operating or trip arms 33 are resiliently adjustable to vary the degree of movement of the blades, and to enable the latter to be adjusted for operation in unison, as shown in Fig. 4. Rotative movement is imparted to the pin 9 through the reciprocating rods 25, 26, and arms 33. Each of the arms is bent back upon itself, the bent back or shorter limb 34 extending into a diametral slot in the pin 9 in which it is secured, while the longer limb lies in an adjacent transverse slot or opening extending in substantially the same axial plane as the diametral slot. An adjusting screw 35 threaded in the pin 9 with its end against the longer limb enables the pendant end of the latter to be adjusted. The trip arm is constructed of resilient material, the limbs being forced apart by the screw against the resiliency of the material, and recoiling toward their normal position when the screw is retracted. Also the arm will be flexed by contact with its operating block in case there is any undue resistance in the operating of the blades. Adjustments to the operation of the blades and straining or other injury to the parts are thus avoided.

The rock shaft 5 is given an oscillating movement by means of a cam 36 mounted on a pulley 37 driven by any convenient source of power. A crank arm 38 secured to shaft 5 carries a cam roller 39 adapted to contact with the periphery of the cam and is resiliently urged toward the latter by a tension spring 40.

As mentioned above, as many groups of cleaning units mounted side by side on the supporting bar 18 all operated from the rock shaft 5, may be employed as desired, so a

plurality of threads of yarn of the same, or of different diameters may be simultaneously cleaned in the same apparatus. The construction above described enables the plurality of groups of cleaning units to be set up without the aid of skilled mechanics, as the hubs 22 carrying the groups of cleaning units are readily attached to the supporting bar 18 by reason of their open slots below and the set screws 23. Rock shaft 5 slips into the bearings provided for it in the brackets 16, and pulley 37 may then be positioned with its center at any operative distance from that of the rock shaft, which distance may vary considerably. Rocker arm 31 may now have its open slot slipped over the rock shaft with its transverse pin engaging the slot of the lever 29. The arm 31 is then secured by the set screws 31^a in proper operative position upon the rock shaft.

The operation of the device of Figs. 1, 2, and 4 will be understood from the foregoing description, a brief outline thereof being substantially as follows: The impurities collected in the various cleaning units are held by the blades until the latter are raised by operation of the rock shaft 5 to effect longitudinal movement of one or the other on rod 25 or 26. Movement of one rod, as shown in Fig. 2, will bring the lugs 32 into contact with one set of trip arms to release every alternate unit, while subsequent operation of the other rod will release the other alternate units. This movement of rods 25, 26 is effected by rocking of arm 31, imparting rocking movement to lever 29 by engagement of the pin 30 of the rocker arm in the terminal slot of the lever. The curved face of the lever 29 engages the corresponding face of the operating lug 28 of rocker arm 27, moving the latter in one direction to operate one group of units. The terminal of lever 29 passes by the engaging terminal of lug 28, the rocker arm 27 and blades of each cleaning unit then returning to normal position. The rocking of the arm 31 in the opposite direction will, in a similar manner, operate the other group of cleaning units.

In the modification of Fig. 3 the construction of the cleaning units, supporting bar 1, bracket arm 20, etc., is generally similar to that in Fig. 2, but the means for reciprocating the rods 25 and 26 is modified. As shown, the pulley 37 carries a cam 41 having a projection 42, and a diametrically disposed depression 43, adapted to engage the roller 39 on the arm 38. A rocker arm 44 is secured intermediate its ends on the rock shaft 5, to the opposite ends of which the bent terminals of the rods 25 and 26 are respectively connected. This provides a direct connection between the rock shaft and the reciprocating rods, and is somewhat

simpler than the construction of Fig. 2, but is not quite so easily assembled or disassembled.

In operation this form is similar to that of Figs. 1 and 2, but it will be noted that as the cam 41 rotates, the projection 42 and depression 43 come alternately into contact with the roller 39 to operate the releasing mechanism. When the projection 42 engages the roller, the arm 38 and rock shaft 5 are operated so as to move rod 25 longitudinally toward said shaft while rod 26 moves in the opposite direction. The lugs 32 on the rod 25 will thus be brought into engagement with the adjustable arms 33 of one group of alternate cleaning units and the blades of these units will be raised to allow the collected impurities to be swept out by the moving yarn. When the depression 43 engages the cam roller, the rock shaft 5 will be oppositely rotated under influence of the tension spring 40 to bring the lugs 32 of rod 26 into contact with the operating arms 33 of the other set of alternate units to similarly release impurities lodged therein. It will thus be seen that the cleaning units are released in alternating groups and that there is a consequent tendency to maintain constant tension on the yarn at all times.

In the modification of the operating mechanism of Figs. 5, 6, and 7 the general arrangement of cleaning units is the same as in Figs. 2 and 3. In this case a bar 45 is mounted to slide longitudinally on the under side of supporting bar 1, screws 46 engaging in slots in this slide bar and threaded into bar 1 for this purpose. This slide bar is provided with a pin 47 disposed adjacent each cleaning unit and arranged to contact with the tension lever 15 pivoted on the spindle 9 as above described. The integral extension 14 of the spring 13 is looped around the tension lever 15. Normally the slide bar is pulled to the right by a coiled spring 48 connecting it with bar 1. Abutting against the end of the slide bar and slidabale in the hub 21 is a push pin 49, the outer end of which is adapted to be engaged by an arm 50 attached to rock shaft 5 by means of an open slot and set screw. A cam 51 is provided for imparting movement to the rock shaft 5, as in the preceding modifications, but this cam differs somewhat from those heretofore described inasmuch as its peripheral cam surface is circular except for a comparatively small angle where there is a depression 52. In consequence the cam roller 39 will, for the greater part of the revolution of the cam, be pushed to the extreme right, thus holding the slide bar 45 in extreme position to the left and acting upon tension levers 15 so as to tighten the tension springs 13 of the cleaning unit blades to hold them against their beds 8.

Once in each revolution of the cam, the roller 39 will drop into the depression 52 and permit the slide bar 45 to be moved to the right under the influence of spring 48, thus releasing the tension of the blades 6^a and 6^b which will then instantaneously jump up under the pressure of the massed impurities lying wedged under them, and the impurities will be swept out by the running yarn. 75

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 89

It is also to be understood that the language used in the following claims is intended to cover all of the generic and specific features of the invention herein described, and all statements of the scope of the invention which, as a matter of language, might be said to fall therebetween. 95

Having described my invention, what I claim as new and desire to secure by Letters Patent is:—

1. In an apparatus for removing impurities from yarn, in combination, means adjacent the yarn to remove and hold the impurities, means actuated at intervals to release said impurities, and means for adjusting the timing of said releasing means. 100

2. In a yarn cleaning apparatus, in combination, a plurality of cleaning units for removing impurities from the yarn passing through the same, and means for operating said units in groups to release impurities removed from the yarn. 105

3. In a yarn cleaning apparatus, in combination, a plurality of cleaning units arranged in series formation for removing and holding impurities from a running yarn, and means for operating said units alternately in groups to release said impurities. 110

4. In a yarn cleaning apparatus, in combination, a plurality of means adjacent a yarn passing through the same adapted to remove and hold impurities carried by the yarn, and means actuated at intervals to operate said means alternately in groups to release said impurities. 115

5. In a yarn cleaning apparatus, in combination, a plurality of units adjacent a yarn and adapted to remove and hold impurities carried thereby, means actuated at intervals to operate the units alternately in groups to release said impurities and means forming a part of said last named means for rendering the same adjustable. 120

6. In a yarn cleaning apparatus, in combination, a plurality of means adjacent a yarn and adapted to remove and hold im- 125

purities carried thereby, means actuated at intervals to operate said means alternately in groups to release said impurities, and means to individually adjust the removing means.

7. In a yarn cleaning apparatus, in combination, a plurality of means adjacent the yarn adapted to remove impurities therefrom, and means including a plurality of 10 longitudinally reciprocable rods actuated at intervals to operate said means alternately in groups.

8. In a yarn cleaning apparatus, in combination, a plurality of means adjacent the 15 yarn adapted to remove impurities therefrom, and means actuated at intervals to operate said means alternately in groups to release said impurities, said last mentioned means being operatively connected to a cam 20 actuated shaft.

9. In a yarn cleaning apparatus, in combination, means for removing impurities, a longitudinally reciprocating rod, and a resiliently adjustable arm connecting said 25 means to said rod.

10. In a yarn cleaning apparatus, in combination, means for removing impurities, a longitudinally reciprocating rod, a resiliently adjustable arm connecting said means to 30 said rod, and a cam operated shaft connected to said rod for reciprocating the latter.

11. In a yarn cleaning apparatus, in combination, a plurality of means for removing and holding impurities, means for releasing 35 said impurities from said first mentioned means, said last means including reciprocating rods each operatively connected to a plurality of said first mentioned means.

12. In a yarn cleaning apparatus, in combination, a plurality of adjustable means for removing and holding impurities, means for releasing said impurities from said holding means, said last means including a pair of reciprocating rods, each rod being connected to alternate holding means, and a cam operated shaft connected to said rods.

13. In a yarn cleaning apparatus, in combination, a plurality of means through which said yarn is adapted to pass, said means being adapted to remove and hold impurities from the yarn, means actuated at intervals to operate said means alternately in groups to release said impurities, said last mentioned means including a plurality of longitudinally reciprocable rods, and means to simultaneously reciprocate said rods in opposite directions.

14. In a yarn cleaning apparatus, in combination, a plurality of adjustable means 60 through which said yarn is adapted to pass, said means being adapted to remove and hold impurities from the yarn, means to operate said first means alternately to release said impurities, said last means including reciprocating rods, and means to simultaneously

reciprocate said rods in opposite directions, each of said gripping means operating to release the impurities only upon movement of its operating rod in one direction.

15. In a yarn cleaning apparatus, in combination, a plurality of means adjacent the 70 yarn adapted to remove and hold impurities, and means for operating said first means at intervals to release said impurities, said last means including a shaft and a cam wheel 75 for reciprocating said shaft.

16. In a yarn cleaning apparatus, in combination, a plurality of means through which 80 said yarn is adapted to pass, said means being adapted to remove and hold impurities, means for operating said first means alternately at intervals to release said impurities, said last mentioned means including a plurality of reciprocating rods, a shaft, a rocker arm on said shaft connected on opposite ends 85 to said rods, and a cam wheel for reciprocating said shaft alternately in opposite directions.

17. In a yarn cleaning apparatus, in combination, means for removing impurities 90 from a running yarn including a support, a pin mounted on said support, yarn engaging means, mounted on said pin, and means contacting said pin and anchored to said yarn 95 engaging means to yieldingly hold the latter in position.

18. In a yarn cleaning apparatus, in combination, means for removing impurities from a yarn including a support, a pin mounted on said support, blades on said pin, 100 and means disposed between said blades for yieldingly holding the same in a position at which they will operatively engage said yarn.

19. In a yarn cleaning apparatus, in combination, a pair of yarn engaging members, 105 means for mounting said members and permitting of a movement of the same in a number of different directions, and means associated with said mounting means and members for yieldingly co-acting with the 110 latter to normally retain the same in operative relationship.

20. In a yarn cleaning apparatus, in combination, a plurality of groups of cleaning units disposed side by side, a rocker shaft 115 extending adjacent said groups and operatively connected to the units thereof, and means for oscillating said rocker shaft.

21. In a yarn cleaning apparatus, in combination, a support, a bracket arm detachably secured to said support, a plurality of 120 cleaning elements carried by said bracket arm, and means adjacent said support for operating said cleaning elements.

22. In a yarn cleaning apparatus, in combination, a supporting bar, a bracket arm having a slotted projection for attachment to said bar, a plurality of cleaning units carried by said bracket arm, a rocker shaft adjacent said supporting bar, and operative 125 130

connections between said shaft and units whereby to release from said units the particles removed thereby from said yarn.

23. In a yarn cleaning apparatus, in combination, a support, a bracket arm detachably secured to said support, a supporting bar carried by said bracket arm extending therealong and spaced therefrom, and a plurality of cleaning units carried by said supporting bar.

24. In a yarn cleaning apparatus, in combination, a supporting bar, a plurality of bracket arms disposed side by side and carried by said supporting bar, yarn cleaning elements carried by each of said bracket arms, an operating shaft disposed adjacent each of said bracket arms, and operative connections between said shaft and said cleaning elements whereby to release from said elements the particles removed thereby from said yarn.

25. In a yarn cleaning apparatus, in combination, a cleaning unit having yarn engaging means and a pin for operating the same, and a resiliently adjustable operating arm secured to said pin.

26. In a yarn cleaning apparatus, in combination, a cleaning unit having yarn engaging means and a pin for operating the same, and an operating arm having a looped end secured to said pin and arranged to adjust said arm.

27. In a yarn cleaning apparatus, in combination, a supporting bar, a plurality of cleaning elements carried by said bar, a longitudinally movable bar, and resilient connections between said bar and said elements for operating the latter.

28. In a yarn cleaning apparatus, in combination, a supporting bar, a plurality of cleaning elements carried by said bar, an

operating bar slidably mounted on said supporting bar, means for reciprocating said operating bar, and operating connections between said operating bar and said cleaning elements.

29. In a yarn cleaning apparatus, in combination, yarn engaging means, resilient means stressed for yieldingly holding said yarn engaging means in operative position, and means for diminishing the stress on said resilient means at intervals, whereby impurities held by said yarn engaging means are released.

30. In a yarn cleaning apparatus, in combination, yarn engaging means, resilient means stressed for yieldingly holding said yarn engaging means in operative position, and a slidably mounted bar operatively connected to said resilient means for periodically diminishing the stress on said resilient means whereby impurities held by said yarn engaging means are released.

31. A yarn cleaner comprising, in combination, a support, groups of cleaning units fixed parallel to one another upon said support, the units of each group being linearly disposed, a rocker shaft held by said support transversely to and adjacent to all of said groups, tripping means for the cleaning units, means attached to the rocker shaft for engaging said tripping means, a cam arm fixed to said rocker shaft, a cam engaged with said cam arm, and means for operating said cam.

In testimony whereof I affix my signature in the presence of two witnesses.

ROBERT GOULD JENNINGS.
